UNITED STATES PATENT OFFICE.

CHARLES L. PAULUS AND ROBERT KAUCH, OF DAYTON, OHIO.

MACHINE-GUN SYNCHRONIZER.

Application filed May 8, 1925. Serial No. 28,620.

This invention relates to aircraft machine gun synchronizers, and more particularly to a synchronizer operated by the intermittent explosion pressure impulses of one of the cylinders of the engine of an aircraft.

The principal object of the invention is to provide a machine gun synchronizer consisting of a valve tapped into the rearmost engine cylinder and normally held closed, to be opened only so long as the delivery of pressure impulses to the machine gun is desired, and a trigger motor on the machine gun connected through a pressure line with the valve, the latter being controlled through a suitable cable extending to a lever mounted preferably on the joy-stick to enable the operation of the valve to fire the gun in the control of the ship.

Other objects of the invention will be brought out in the course of the following description, in which reference is made to the accompanying drawing illustrating the invention.

Fig. 1 of the drawing is a more or less diagrammatic view of a machine gun synchronizer installation, made in accordance with our invention.

Fig. 2 is an enlarged longitudinal section through the trigger motor of the machine gun, and

Fig. 3 is an enlarged isolated detail showing the valve and its operating connection.

Referring to the drawing, the reference numeral 10 indicates the engine having a propeller 11 mounted on its crankshaft 12. The machine gun 13, mounted on the aircraft at some point to the rear of the engine to be under the control of the pilot or gunner, is arranged to fire between the blades of the propeller 11. The machine gun is provided with a trigger motor 14 which receives intermittent pressure impulses through a line 15 extending from a valve 16 tapped into the rearmost cylinder of the engine 10. The valve 16 is controlled by a wire passing through a flexible casing 17 of the Bowden type, which extends from the valve to the cockpit of the pilot or gunner where a hand lever 18 is provided for manual operation. In the form illustrated this lever is shown pivoted on a bracket 19 carried on the joystick 20 in the pilot's cockpit. Depending on which one of the cylinders the valve 16 is mounted, it will be seen that the pressure impulses will occur at different intervals of crankshaft travel. It

is therefore necessary to locate the propeller 11 in proper angularity to enable firing between the blades as it turns. For this purpose a dowel pin 21 is provided conveniently on a flange 22 of the propeller mounting which will be engaged in a location hole provided in the hub of the propeller when the propeller is installed.

The valve 16 has a lever 23 which is normally held in closed position by a spring 24 acting between a clip 25, pivoted to the end of the lever 23 and a bracket 26 on the side of the valve 16. The control wire 27 in the casing 17 previously referred to, has connection with the clip 25 and at its opposite end with the lever 18 in a suitable manner, and when the joy-stick 20 is grasped it is possible at the same time to hold the lever 18 with the valve 16 opened. In this way the machine gun 13 can be fired so long as desired, while the pilot is maneuvering the ship. An advantage in the provision of a valve which is normally closed is that no power of the engine is consumed uselessly at a time when the gun is not to be fired and the life of the mechanism is also increased.

The trigger motor 14 comprises a base 28 mounted in any suitable manner on the side of the machine gun adjacent the trigger mechanism and held suitably by a bolt 29. The motor consists of a cylinder 30 which communicates through the pressure line 15 previously referred to, with the valve 16 on the engine cylinder. A nipple 31, threading into the open end of the cylinder, is provided for connection with the semiflexible tubing, of which the pressure line 15 consists. A piston 32 is reciprocable in the cylinder 30 under the pressure impulses communicated through the line 15 from the engine cylinder, but is normally held in an inoperative position by a spring 33 acting against the rearward side of the piston at the inner end of the cylinder.

A trigger operating plunger 34 is reciprocable and held from rotation in a guideway 35 extending transversely with respect to the cylinder 30 in the base 28. The plunger 34 has a cam-shaped end 36 projecting into the cylinder 30 into a notch 37 in the side of the piston 32. The plunger 34 is normally held in an inoperative position by a spring 38 when the piston 32 is in its normal inoperative position. The intermittent pressure impulses delivered to the piston 32 reciprocate

the plunger 34 to fire the gun 13. When the propeller 11 has been properly located as above described, it is insured that these power impulses will occur at the proper intervals to avoid hitting the blades.

We claim:

1. In a machine gun synchronizer for aircraft, the combination with the engine and propeller of said aircraft, of a valve tapped into a cylinder of said engine, means for remotely controlling said valve, a machine gun remotely situated with respect to said engine, and a trigger motor for said machine gun having a pressure line extending from said valve to deliver intermittent pressure impulses for the operation of said machine gun.

2. In a machine gun synchronizer for aircraft, the combination with the engine and propeller of said aircraft, of a valve having communication with the interior of one of the cylinders of said engine, spring means normally holding said valve in closed position, a remotely located manually operated lever for holding said valve opened against the spring pressure for the length of time it is desired to fire the gun, a machine gun remotely located with respect to said engine, a trigger motor mounted thereon, and a pressure line connection for said motor with said valve.

3. In a machine gun synchronizer for aircraft, the combination with the engine and propeller of said aircraft, of a valve having communication with the interior of one of the cylinders of said engine, spring means normally holding said valve in closed posi-

tion, a remotely located manually operated lever for holding said valve opened against the spring pressure for the length of time it is desired to fire the gun, said lever being mounted on the joystick of said aircraft to be operated while gripping the stick in the control of the ship, a machine gun remotely located with respect to said engine, a trigger motor mounted thereon, and a pressure line connection for said motor with said valve.

4. An engine pressure operated impulse device comprising a manually controlled valve tapped into the engine cylinder, a tube leading therefrom, an impulse cylinder connected to the far end of said tube, a piston in said cylinder to be operated from a normal inoperative position by intermittent pressure impulses from the cylinder communicated through said tube, and means operated by said piston.

5. An engine pressure operated impulse device comprising a manually controlled valve tapped into the engine cylinder held normally in closed position under spring pressure to be held open manually so long as operation of the impulse device is desired, a tube leading from said valve, an impulse cylinder connected to the far end of said tube, a spring pressed piston operating in said cylinder to be moved against the spring pressure by the engine pressure impulses, and means operated by said piston.

In testimony whereof we affix our signatures.

CHARLES L. PAULUS.
ROBERT KAUCH.
